BEAUTIFYING SET FOR LADIES' HAND BAGS

Original Filed Aug. 19. 1926

Patented Dec. 13, 1927.

1,652,771

UNITED STATES PATENT OFFICE.

KARL DEUBEL, OF NEWARK, NEW JERSEY.

BEAUTIFYING SET FOR LADIES' HAND BAGS.

Application filed August 19, 1926, Serial No. 130,121. Renewed November 4, 1927.

This invention relates to improvements in toilet sets, particularly for use by ladies, and more particularly to a toilet set including a hair curling apparatus, and it is the 5 principal object of the invention to provide a toilet set which may form a part of a case or hand-bag such as usually carried by ladies.

Another object of the invention is the provision of a practical and handy toilet set 10 which embodies in a compact form, all of the necessities which a lady requires for executing her toilet particularly when she is away from home.

A further object of the invention is the 15 provision of a hair curling and dressing set for ladies, including foldable curling tongs, having hollow handles for the reception of various toilet articles, as for instance perfume bottle, lip stick, eye-brow pencil, and 20 the like.

A still further object of the invention is the provision of a toilet set for ladies and actors, and the like, including an alcohol lamp and burner, and means of readily igniting the wick of the same, as well as means 25 for supporting the curling iron or tongs during heating.

It is also one of the features of my invention to provide a toilet set adapted to contain a mirror, a comb, a manicure set, a 30 powder container and puff, and in short words, all the necessities for a lady for completing her toilet when traveling etc.

These and other objects and advantages 35 of my invention will become more fully apparent as the description thereof proceeds and will then be more specifically defined in the appended claims.

Fig. 1 is a perspective view of a case, such 40 as commonly carried by ladies, embodying my improved toilet set.

Fig. 2 is a transverse sectional view thereof.

Fig. 3 is a side elevational view of a handbag, such as commonly carried by ladies, 45 embodying my improved toilet set.

Fig. 4 is a detail view of the foldable curling irons, partly in section, so as to more clearly show the hollow construction thereof.

50 Fig. 5 is a side elevational view of the foldable combination finger nail clipper, file and buffer.

Fig. 6 is a perspective view thereof, showing same in an open position.

55 Fig. 7 is a top plan view of the alcohol lamp and burner.

Fig. 8 is a longitudinal sectional view thereof, taken on the line 8—8 of Fig. 7.

Fig. 9 is a perspective fragmentary view showing the method of adjustably holding 60 the tray member, in any desired inclined position.

Fig. 10 is a sectional detail view thereof.

The case 10, commonly known as a vanity case, or the like, has its cover 11 hinged 65 thereto in any well known manner, and both may be made of a suitable material, such as wood, fibre, covered with silk, leather or the like, or may be made of polished aluminum, or enameled metal. The handle 12 is secured to one end of the case 10, so as to furnish a suitable carrying medium. The case 10 is also fitted with a snap catch 13, adapted to engage the latch 14 attached to the cover 11, so as to securely hold the said cover in a 70 closed position. It being understood that I do not necessarily limit the use of my invention in particular to vanity cases as above described and set forth, but to all classes and 75 types of vanity cases, such as may be, from time to time, depending largely upon the current styles, modes, etc., carried by ladies.

Referring in particular to the embodiment 80 of my improved device in a vanity case, the tray member, adapted to hold the various articles, comprises a tray member proper 14, hinged at one end or side, in the well known manner, to the upper portion of the case 10, adjacent to the cover 11, so as to provide 85 a compartment 15, below the said tray member proper. The secondary tray member proper 16, is hinged to the tray member proper 14, in the well known manner. The said tray members proper 14 and 16 being 90 of sufficient and suitable size to entirely enclose or cover the said compartment 15, when in a closed position, as clearly shown in Fig. 2 of the accompanying drawings.

The secondary tray member 16 is provided 95 with an extended element 17, positioned adjacent to the side 18 of the case 10. The extended element 17 has formed or cut there-in apertures to receive the adjustable member 19, a thumb screw or the like, which is extended through the guide element 20 of 100 the side of the case 10, which is provided with an elongated slot having slightly tapered edges, adapted to receive the tapered edges of the clamping block, which is adjustably attached, by a threaded aperture or 105 the like to the threaded extremity of the adjustable member 19. The latter described 110

construction being such as will permit the secondary tray member 16, to be held in any desired angular position, such as designated by the reference numeral 22, Fig. 2, as a means of permitting the mirror 23, normally held in the cover 11, when inserted in the clip 24, adapted to slidably receive the lower edge of the mirror 23, to be held in any desired angle, such as designated by the reference numeral 25, as is desirable and more convenient to the lady using the said mirror. It being understood that the mirror 23, is of suitable size to slidably engage inside the cover 11, and that the mirror 23, and the secondary tray member 16, are provided, respectively, with depending members 26 and 27, straps or the like to facilitate the manipulation thereof.

The tray member proper 14 and the secondary tray member 16, are adapted to hold or support the comb 28, which is held thereon by a holder 29. The powder container 30, a curling tong 31, the combination finger nail device 32, and an alcohol container 33 with combined accoutrements, are removably held on the said tray members 14 and 16.

The combination finger nail device as illustrated in Fig. 5, comprises a buffer 34 held in a suitable frame 35 attached to the nail clipper member 36, provided with a cutting edge 37, or extremity, adjacent to a similar cutting edge 38, of the second nail clipper member 39, which is pivotally attached, as at 40, to the nail clipper member 36.

The said cutting edges 37 and 38 being normally held in a disengaged position, by a flat spring 41, attached at one extremity to the second nail clipper member 39. The nail cleaner member 42 is provided with a free extremity, pointed, as at 43, and is pivotally attached, at its other extremity, as at 44, to the nail clipper member 36. The said nail cleaner member 39 is provided with the usual file finished surface.

The curling tong or iron, Fig. 4, comprises the customary iron or shank 45 and 46, pivotally connected, as at 47, to the inner shank ends the hollow handles 48 and 49, are pivotally secured, as at 50 and 51. The outer ends of the hollow handles are closed by screw caps 52 and 53, respectively, allowing ready access to the interior of the hollow handles, a perfume bottle 54 closed by a ground glass stopper 55, is located in one of the hollow handles, while the other handle contains a lip stick 56, cosmetic, and an eye-brow pencil 57, in a common holder 58.

The alcohol container 33, Figs. 7 and 8, has a removable cover 59, held in place by a latch member 60, adapted to slidably engage the container. The container, contains a material 61 for instance, asbestos saturated with alcohol, part of which extends through an opening in the container, constituting a wick.

The igniter 62 is mounted on top the container, opposite the wick, and comprises a cerium or other suitable striking face 63 adapted to be engaged by a striker 64 of suitable material to produce by friction a spark for the ignition of the wick. A support 65 is suitably mounted on top the container near the striker which may be pivoted to its upper face, as at 66. At its lower end the support is attached to a piece 67, journaled in suitable ears on the top of the container, and its upper edge is suitably caved to form a rest for the curling tong, while the tongs thereon are heated over the flame of the burning wick, a shoulder being provided to limit the movement of the striker toward the wick for holding the support in the position to support the tongs, when in rest, it may be folded against the top of the container.

Referring in particular to Fig. 3 of the accompanying drawings, the hand-bag 68, provided with hinged members 69 and 70, and a depending handle 71, strap or the like, is of common construction, such as usually carried by ladies. It being understood that I do not necessarily limit the further use of my improved devices to hand-bags of the particular type above described, but to all types and classes of hand-bags such as may be carried and used by ladies.

The operation of my improved devices will be clear from the above detailed description without further explanation, and it is to be understood that such changes may be made in the general arrangement and in the construction of the minor details of my invention as come within the scope of the appended claims without departure from the invention.

Having thus described my invention, what I claim as new and desire to protect by Letters Patent of the United States is as follows:

1. A vanity case consisting of a case, a cover hinged to the said case, a tray member hinged to the said case, a secondary tray member hinged to the said tray member, said tray member and said secondary tray member adapted to cover the said case, said secondary tray member provided with a means of holding the said secondary tray member in any desired angular position.

2. A vanity case consisting of a case, a cover hinged to the said case, a tray member hinged to the said case, a secondary tray member hinged to the said tray member, said tray member and said secondary tray member adapted to cover the said case, said secondary tray member provided with a means of holding the said secondary tray member in any desired angular position, a mirror normally held in the said cover, said secondary member provided with a clip adapted to hold the said mirror.

3. A vanity case consisting of a case, a cover hinged to the said case, a tray member hinged to the said case, a secondary tray member hinged to the said tray member, said tray member and said secondary tray member adapted to cover the said case, said secondary tray member provided with a means of holding the said secondary tray member in any desired angular position, a mirror normally held in the said cover, said secondary member provided with a clip adapted to hold the said mirror, said secondary tray member provided with holders as a means of holding a toilet set.
4. A vanity case consisting of a case, a cover hinged to the said case, a tray member hinged to the said case, a secondary tray member hinged to the said tray member, said tray member and said secondary tray member adapted to cover the said case, said secondary tray member provided with a means of holding the said secondary tray member in any desired angular position by means of an adjustable member positioned in an aperture formed in the extended element of the said secondary tray member, said adjustable member extended through a guide element of the side of the said case, said guide member provided with an elongated slot having tapered edges adapted to receive the tapered edges of a clamping block adjustably attached to the said adjustable member.

In testimony whereof I have affixed my signature.

KARL DEUBEL.
